CLAIM

The ornamental design for mailbox mail delivery signal, as shown and described.

DESCRIPTION

FIG. 1 is a front plan view of a mailbox mail delivery signal of the present invention shown mounted on a mailbox, signal plate, and connecting chain being shown in phantom; FIG. 2 is a side elevational view thereof, the right and left side elevational views being identical; FIG. 3 is a bottom plan view thereof; FIG. 4 is a top plan view thereof; and, FIG. 5 is a rear elevational view thereof. The phantom lines showing the mailbox, the signal plate, and the chain connecting the signal plate to the mailbox forms no part of the claimed design.
